[57] ABSTRACT

A method for producing an aesthetic field suspension comprising preparation of a body of gelatinous material having high yield value, then inserting a similar gelatinous material of similar characteristics therein, said similar gelatinous material being optically contrasting with said body of gelatinous material, then allowing the high yield value of the materials to hold the similar material in said body material in substantially permanent position relative to said body; the disclosure further and specifically defining a method for inserting the similar material in said body in frozen form or by means of a hollow tubular member which may be moved around in the body during the insertion of the similar material therein to form geometric or other aesthetic patterns of the similar material in the body material; the disclosure also defining a novel product related to said method.

AESTHETIC FLUID SUSPENSION AND ITS PREPARATION

This application is a continuation - in - part of co-pending application to William B. Lewellen for a method for producing an aesthetic fluid, Ser. No. 593,850, filed Nov. 16, 1966 and now abandoned.

BACKGROUND OF THE INVENTION

Various gelatinous materials having high yield value are used in the production of cosmetics and a substantial variety of products and the characteristics of these materials are generally known to those skilled in the art by way of the following references.

Ref. No. 1. Paint Flow and Pigment Dispersion, by Temple C. Patton, Interscience Publishers, 1964, Library of Congress Catalog Number: 64-23856.

Ref. No. 2. Emulsions: Theory and Practice, by Paul Beecher, Reinhold Publishing Corporation, 3rd. Printing, 1961, Library of Congress Catalog Number: 57-14847.

Ref. No. 3. B. F. Goodrich Company - Carbopol Water-Soluble Resins, Service Bulletin GC-36, from the

The foregoing references fully define materials having "high yield value" and accordingly, this term as used herein refers to material having a certain minimum sheer stress resistance that must be exceeded before flow will take place.

SUMMARY OF THE INVENTION

The present invention relates to a method for producing an aesthetic fluid suspension, and more particularly, to a method for producing a permanent aesthetic fluid suspension in water soluble or other resin solutions; the invention also relating to a novel product.

The method of the invention is broadly concerned with the inserting of one gelatinous material in the other to establish permanent stationary optical boundaries between materials of contrasting character so as to provide an aesthetic effect which is created by the product in a transparent or translucent container. Additionally, the invention relates to a product wherein two gelatinous materials are so related that they define permanent stationary optical boundaries relative to each other and wherein one material is related to the other in an optical contrasting disposition, and further materials of said product are miscible in character and contain relatively non-soluble pigment material permanently held in suspension in the gelatinous material, such that the "high yield value" characteristics thereof maintain said non-soluble material in suspension and thereby maintain permanent and stationary optical boundaries of contrasting character and respective aesthetic effects.

Accordingly, it is an object of the present invention to provide a novel method for producing aesthetic fluid suspensions in water soluble resin solutions.

Another object of the invention is to provide a novel method, wherein optically contrasting portions of water soluble or other resin solutions may be inserted in other bodies of similar water soluble resin solutions so as to display a trademark in the clear body of a resin solution in a container, which may be a conventional transparent glass or plastic container.

Another object of the invention is to provide a novel method for producing an aesthetic fluid suspension, wherein a portion of water soluble or other resin solu-

tion may be prepared in a foam condition and then inserted in various patterns through a hollow tubular conduit and into another body of a similar water soluble resin solution, whereby the high yield stress resistance or value of the water soluble resin solution retains a pattern of bubbles therein so as to provide and maintain an aesthetic effect.

Another object of the invention is to provide a novel method for producing an aesthetic fluid suspension comprising the freezing of a portion of a water soluble resin solution, either of a given color, optical contrast or of foamed resin solution, then inserting the frozen portion of water soluble resin solution into another, but unfrozen, body of substantially transparent or translucent water soluble resin solution, whereupon the frozen portion of resin solution may ultimately attain the same temperature as the body of resin solution and be retained therein in a suspended state, such that contrasting optical character of the originally frozen portion is visible internally of the body in which it is inserted.

Another object of the invention is to provide a very novel method of producing an aesthetic fluid suspension, wherein a small body of resin solution is placed in a larger body of resin solution and wherein the small body is either of optically contrasting color or foamed character, such as to be seen suspended in the clear transparent or colored translucent body of resin solution which may be contained in a transparent or translucent container.

Another object of the invention is to provide a product related to the method of the invention; said product including a plurality of miscible gelatinous materials, each having a high suspension yield value, one of the gelatinous materials disposed in the other gelatinous material so as to create an optical contrast relative thereto, and a container containing said plurality of gelatinous materials in relation to each other, whereby an aesthetic effect is created by viewing the optically contrasting material in said container through the transparent or translucent wall thereof.

Another object of the invention is to provide a product composed of a plurality of gelatinous materials having high suspension yield value and disposed adjacent to each other, said gelatinous materials having pigmentation material therein of optically contrasting character and of non-soluble characteristics relative to the gelatinous material, whereby the high suspension yield value maintains the pigment material in suspension therein to sustain optical boundaries between the optically contrasting characteristics of the gelatinous materials of the product.

Further objects and advantages of the invention may be apparent from the following specification, appended claims and accompanying drawings, in which:

BRIEF DESCRIPTION OF THE DRAWINGS

FIG. 1 is a diagrammatic view of apparatus used in producing an aesthetic fluid suspension in accordance with the method of the present invention; FIG. 1 showing containers in section and portions of the apparatus in elevation;

FIG. 2 is a vertical sectional view of a hollow cylindrical container showing a substantially transparent mechanism containing transparent water soluble resin solution, wherein a relatively smaller portion of a similar resin is suspended in a spiral form in the body of resin solution contained in the container, and wherein the

spiral form of the resin solution may be foamed resin solution or colored to provide an optical contrast;

FIG. 3 is a view similar to FIG. 2, showing a small body of resin solution disposed in a larger body of resin solution held in a transparent container, the small body of resin solution having contrasting colored letters or a trademark, the small body being initially frozen, in accordance with a method of the invention and inserted into the larger body of transparent resin solution;

FIG. 4 is a fragmentary sectional view taken from the line 4—4 of FIG. 3;

FIG. 5 is a sectional view of a product in accordance with the present invention; and

FIG. 6 is a side elevational view of a flexible plastic container shown broken away and in section and containing a modified aesthetic fluid suspension in accordance with the invention.

DESCRIPTION OF THE PREFERRED EMBODIMENTS

In accordance with the present invention, aesthetic fluid suspensions are produced in gelatinous water soluble resin solutions and particularly those having very high yield value. Such resin solutions are described in the foregoing Ref. No. 3; B. F. Goodrich Chemical Company Service Bulletin GC-36, and more particularly, directed to Carbopol resins. These are Carboxy Vinyl polymers of extremely high molecular weight, and being substantially hydrophylic and require neutralization by base materials to neutralize acid properties thereof. These resin solutions are water soluble resins and are characterized by their ability to hold bubbles or other material in suspension, even those materials having a higher specific gravity than the resin solution itself. As for example, such resin solutions may suspend small steel balls and hollow table tennis balls, such that the steel balls will be held upward in the resin solution and the hollow tennis balls may be held down in permanent position.

These resin solutions may be colored or transparent and are preferably sold in accordance with the cosmetic trade in clear or translucent glass or plastic containers, or the like, such that aesthetic fluid suspensions in accordance with the present invention, may be very attractive for sales or advertising purposes since the fluid suspensions, according to the present invention, may be used to display trademarks internally of the material in the container or to exhibit very ornamental designs created by optically contrasting suspensions, either in the form of foamed portions of the resin solution, bubbles in certain patterns or contrasting colors of one resin solution relative to another and wherein the one resin solution is in a smaller quantity and suspended in a larger body of the other. The aforementioned optical contrast between the resin solutions may also be used in products to indicate various ingredients which may be viewed through a transparent wall of a product container or by color coding to indicate flavor, scent or other properties.

The contrasting colors of either of a plurality of resin solutions may be attained by use of non-soluble particulate coloring material maintained in suspension in said solutions, it being noted that these materials are miscible within each other, however, the coloring pigments are non-soluble and therefore do not tend to bleed across the optical boundaries established between one

resin solution which is suspended in another resin solution of the type hereinbefore disclosed.

Permanent optical boundaries can be established in a liquid body if that liquid body displays plastic flow (See: Background Ref. No. 1) thus permitting the creation of aesthetically pleasing designs or patterns of attractive colors. As gelled products meeting the requirements of this invention are presently being widely sold, the advantage of making them more distinctive and attractive is apparent. The gelled products referred to are largely in the field of cosmetics, but the application of this art may easily be applied to food products, industrial gelled products, etc.

Optical boundaries of random or preconceived and reproducible configuration are permanent from below freezing, 32° F., to well over 100° F., and can be established in gelled liquids or non-Newtonian liquids which display plastic flow (See: Background Ref. No. 1). This phenomenon is measured by the degree of yield, termed "yield value" in the science of rheology. The liquids referred to may contain water, alcohol, various oils, emulsions, or the liquid may be any liquid or combination of liquids displaying or capable of treatment causing them to display said plastic flow. These liquids may be hereinafter referred to as: the liquid body, the gelled liquid, and/or the media. To demonstrate the establishment of said increased boundaries, the following example is cited: Two outlet of the gelled liquid are prepared being substantially identical in very respect except that one of the bodies contains an agent causing said liquid body to differ optically from the other. If the agent used to create this optical differentiation is non-soluble in the media in question and relatively inert, it is then apparent that the two liquid bodies referred to will be completely miscible and will blend to a homogeneous whole when mixed. It is apparent that boundaries which exist may be optically discernable at the interface of two non-miscible liquids brought into physical contact with each other. A gelled liquid used according to the invention is one consisting principally of water and a water-soluble resin, such as Carbopol No. 940, B. F. Goodrich Chemical Company, and properly neutralized to produce a gelled, transparent liquid displaying the rheological property of relatively high yield; and the coloring agent used in one portion of the gelled liquid body (hereinafter referred to as the first liquid body) to cause optical differentiation from the balance of a clear, transparent or translucent gelled liquid (hereinafter referred to as the second liquid body), is an iron oxide color pigment of relatively small size and the said second liquid body are brought into physical contact an optical boundary will be produced that is retained in configuration until a force, in excess of the yield value of the gelled liquid, is exerted on the mass or some part of the mass. When an aesthetic fluid suspension, in accordance with the invention, is contained in a flexible plastic container, and when squeezing pressure is brought to bear externally thereon; any optical boundary in the suspension may be distorted due to resilient yield of the high yield gelled liquids of the invention, however, when such squeezing pressure is the being previously distorted optical boundary may readily return to its original configuration. Additionally, the aesthetic fluid suspension of the invention, when packaged in a flexible container, may be subjected to high accelerative forces, such as may be caused by dropping

the container on the floor without causing permanent distortion of said optical boundary.

The agent or pigment used to produce the optical boundary in one portion of a gelled liquid must be media non-soluble to successfully maintain that boundary without distortion for long periods of time. If desired, one or more gelatinous liquid bodies, in addition to any non-soluble coloring agent, may contain a soluble coloring agent, such as a dye to color or lightly tint the entire mass. The soluble agent may diffuse, but the media non-soluble agent will maintain the boundary.

An agent used to produce permanent optical boundaries is defined herein as being media non-soluble. This is meant to identify a substance, solid, liquid, or gaseous, that is substantially insoluble in the particular gelled liquid in question. A media non-soluble material, unlike a solute in a solvent, remains in the liquid as a discrete and particulate unit. When such particles are dispersed in a gelled liquid of sufficient yield value, they retain their spaced relationship with the mass of the liquid because their (the particles) relative small size and mass does not exceed the yield value of the gelatinous liquid. When a first gelled liquid body containing such dispersed particles of coloring agent is brought into contact with a second liquid body containing no coloring agent or an agent producing an optical contrast to that of the first liquid body, all those discrete particles, that are media non-soluble will permanently hold their spaced relationship to the entire liquid mass.

It will also be understood that the terms: agent, coloring agent, pigment, pigmenting agent, used herein, are construed to include commonly used pigments that produce all colors including: white, black, all shades of gray, brown, metallic effects (gold, silver, pearlescent effects, etc.), the colors of the visible spectrum, and hazy or cloudy effects, as might be produced when a transparent, translucent, or very finely divided opaque material is dispersed in a liquid. Various degrees of difference in the respective refractive indicas of the dispersed substantially transparent or translucent pigmenting agents, relative to that of the liquid in question, may be employed to cause an optical differentiation. It will also be understood that the coloring agent may be transparent, translucent, opaque, or even invisible under normal conditions of light, but visible when viewed under ultraviolet light or when excited or treated in some other manner.

Also included under the definition of agents used to create optically contrasting conditions in one gelled liquid relative to another body of gelled liquid of substantially identical composition and miscible one in the other, and wherein there is a third body of liquid that is substantially non-miscible and non-soluble in the said gelled liquids. This third non-miscible liquid body may be either pigmented or unpigmented and can be emulsified into a portion of the said gelled liquid by conventional methods (See: Background Ref. No. 2). This non-miscible liquid, by emulsifying may be reduced to small, discrete globules; the resulting emulsion being of excellent stability if properly prepared in a media of liquid, gelled with the Carbopol resins, for example (See: Background Ref. No. 3). It is further understood that this said non-miscible liquid constitutes a discontinuous phase of the emulsion and may be colored or pigmented by an agent that is either soluble or non-soluble in said non-miscible liquid, but if it is to remain in the particles of said non-miscible liquid, it must be non-

soluble in the surrounding gelled liquid body; termed the continuous phase of the emulsion (See: Background Ref. No. 2).

If a gas, such as air, is dispersed into a body of gelled liquid so as to produce a foam, the individual gas bubbles may be small enough such that they may not easily be seen individually in the mass. Such gas bubbles are held relatively permanently in spaced relationship with each other in the mass of the gelled liquid in a manner similar to solid particles of a pigmenting agent. This body of foamed liquid can then be brought into contact with a body of gelled liquid of substantially identical composition, for example, by methods disclosed herein. The particulate pigmenting agents which may be used to effect optical contrasts in adjacent gelatinous bodies according to the invention may range from a molecular size to 0.25 inches.

In cosmetic preparations, the particulate material may range in size from molecular dimensions to 0.025 inches and these foregoing size ranges are preferred examples of the particulate pigment materials used in accordance with the invention and maintained in suspension in the gelatinous materials of the invention to create optical boundaries and various aesthetic effects, as well as indications of various materials in products in accordance with the invention. The operable temperatures under which the gelatinous materials of the invention may remain stable may range between minus 20° F. to 120° F. so as to provide for practical maintenance of optical boundaries in the gelatinous materials of a product in accordance with the present invention and to insure the maintenance of the original aesthetic effects in packaged materials while they are held in inventory or on the shelf pending sale.

Furthermore, the suspension of the particulate non-soluble materials in miscible gelatinous materials prevents migration, of color or optically contrasting materials, from one gelatinous material to another and thus prevents the distortion of optical boundaries normally required to maintain aesthetic effects which are desirable within the product according to the present invention.

As shown in FIG. 1 of the drawings and in accordance with the invention, apparatus is provided for creating certain aesthetic fluid suspensions in accordance with the method of the invention.

A conventional cosmetics container 10 or any other suitable container preferably of transparent material, such as glass, or the like, may be supported on a turntable 12 having a rotating shaft 14 supported centrally of a thrust bearing 16 which carries the turntable 12 on a frame 18. A motor 20 having an output shaft 22 is connected to the shaft 14 and tends to rotate the turntable 12 together with the container 10 around a substantially vertical axis 24. The container 10 may be circular in cross-section or of any suitable hollow cylindrical shape so as to contain a first body 26 of a gelatinous water soluble resin solution, as hereinbefore described. This resin solution may be slightly colored or may be transparent, if desired.

A hollow tubular conduit 28 is inserted into heat body 26 of the resin solution and this conduit 28 is provided with a lower open end 30 adapted to dispense a smaller amount of resin solution in the body of resin solution 26. A flexible tube 32 is connected to the conduit 28, this tube 32 is adapted to receive a water soluble resin solution from a pump 34 having an inlet con-

duit 36 immersed in a second body 38 of a water soluble resin solution which is held in a container 40. In operation, the pump 34 forces the water soluble resin solution 38, as indicated by arrows, upwardly through the inlet 36 and through the tube 32 downwardly through the conduit 28 and out of the end 30. During rotation of the turntable 12 and the container 10, the conduit 30 may be moved upwardly in a direction of the arrow A so as to produce a spiral pattern of the solution 38 in the solution 26, this is caused due to rotation of the container 10 with the outlet 30 of the conduit 28 disposed in spaced relation from the rotational axis 24.

It will be understood that the water soluble resin solution 38 may first be foamed, such that the resin solution contains a large amount of bubbles, whereupon these bubbles inserted in the body of resin solution 26 in spiral form create an optical contrast. Additionally, it will be understood that the resin 38 may be a different color than the resin solution 26 so as to provide an optical contrast.

The disclosure of FIG. 2 illustrates a spiral form of the resin solution 38 which has been foamed and which may be of a slightly different color from the body 26 of resin solution held in the container 10.

In accordance with a modification of the present method, a small portion of the resin solution 38 is provided with colored letters 41 or other indicia which may be written, printed or molded on the portion 38 after it has been frozen. This portion 38 of resin solution may be frozen in any suitable mold and the letters 41 may be produced with a die, or may be otherwise formed, as desired. Various patterns and foamed contrasts or other contrasts may be made in the frozen portion 38 and then the frozen portion 38 may be inserted downwardly into the body 26, as shown in FIG. 3, simply by moving the frozen body of material 38 downwardly in the direction of the arrow B until it has been located at a desired level at which time the body 38 may thaw and attain a thermal equilibrium with the material in the body 26.

The frozen portion 38 may be of the same optical character as the material of the body 26 and the letters or indicia 41 may constitute the only optical contrast in the aesthetic suspension, as shown in FIGS. 3 and 4. Accordingly, the portion 38 may be non contrasting with respect to the body 26 while the printed letters may be optically contrasting relative to the body 26.

As shown in FIG. 5 of the drawings, a container 10 of transparent or translucent material may hold a plurality of gelatinous high yield value materials designated 44 and 46. The material 44 may have pigment particles 48 therein, and the gelatinous material 46 may have pigment particles 50 therein, and all of said pigment particles are non-soluble in the fluids or gelatinous materials 44 and 46 and these fluids are relatively miscible. The high yield value of these gelatinous materials 44 and 46 maintains juxtaposition of the pigment materials 48 and 50 so that when the pigment materials 48 vary in optical character relative to the particulate pigment material 50, optical boundaries 52 and 54 are established, and these boundaries 52 and 54 are readily and clearly visible through the transparent or translucent wall of the container 10.

In the modification of the invention, as shown in FIG. 6 of the drawings, a flexible plastic container 60 is provided with a conventional removable cap 62 enclosing

an open end of the container through which materials may be dispensed from the interior of the container, as desired.

The flexible plastic container 60 is preferably made of transparent or translucent material so that the optically contrasting contents therein and in accordance with the invention may be viewed through the side wall of the plastic container.

The suspension fluids having high yield value are disposed in the container 60 and are of character similar to those hereinbefore described, but contain various products, such as soaps, hair conditioners, body oils, etc. These materials may be in the form of gelled fluids which are of high yield value similar to that described in connection with the disclosure of the Carbopol fluids.

As a specific example of the modification of the invention, three different products 64, 66 and 68 may be maintained in high yield suspension relative to each other in the container 60 and may be optically contrasting so that they indicate to a customer distinct products. As for example, the high yield fluid 64 may contain a bath soap or shampoo soap, the product 66 may contain a hair conditioner, and the product 68 may contain a body oil so that the container may serve as a

complete package for these materials normally used when a person bathes, washes the hair and generally conditions the skin. The closely 60 may be made in various sizes for dispensing a plurality of products in sequence and these products being of generally gelled

material having high yield characteristics conveniently provide for the insertion of one body of material in or between other bodies of material as specifically shown in FIG. 6 of the drawings, and each body of material may be of contrasting color relative to that of the other so that the customer may readily distinguish one product from another during a use thereof, as desired.

It will be appreciated by those skilled in the art that the different products 64, 66 and 68 may be other than those specifically disclosed herein, however, the modification of the invention, as shown in FIG. 6 of the drawings, includes the high yield gelled structural disposition of several different products in a common container and in a generally superimposed layered relationship to each other, such that various products in high yield suspension may be inserted in various dispositions relative to each other for dispensation, as desired.

It will be further appreciated by those skilled in the art that various aesthetic fluid suspensions may be attained in accordance with the present invention, either by inserting a foam of a similar resin solution in a given body of water soluble resin solution or the insertion may be made of a similar colored resin solution or a portion of similar resin solution which has been frozen.

It will also be understood that the inserted resin solutions are thus adapted to create an optical contrast which may be seen through the walls of transparent containers, such as cosmetic containers, or the like.

It will also be understood that such fluid suspensions may be useful for other purposes, as for example, illuminated advertising media, or the like.

It will be obvious to those skilled in the art that various modifications of the present invention may be resorted to without departing from the spirit of the invention.

I claim:

1. An aesthetic fluid suspension comprising:

- A. A first body of gelatinous material having a high suspension yield value,
  - B. A second body of gelatinous material disposed in the first body of material and suspended therein by the high suspension yield value of the gelatinous material, said second body having a substantially similar suspension yield value as the first body, but having an optical contrast with the first body, and
  - C. A container for suitably enclosing the suspension.
2. An aesthetic fluid suspension as described in claim 1, wherein:
- A. The second body of gelatinous material is a foamed.
  - 3. An aesthetic fluid suspension as described in claim 1, wherein:
    - A. The second body of gelatinous material contains a coloring agent which contrasts with the optical character of said first body.

4. An aesthetic fluid suspension as described in claim 1, wherein:

    - A. The second body of gelatinous material has a distinctive form while suspended within the first body.

5. The invention, as defined in claim 1, wherein: said container is provided with a wall adapted optically to expose said bodies of gelatinous material therein.

6. The invention, as defined in claim 1, wherein: said bodies of gelatinous material are miscible; and particulate, non-soluble pigment material in one of said gelatinous materials is adapted to provide said optical contrast.

7. The invention, as defined in claim 6, wherein: the size of said particulate material ranges from a molecular size to 0.025 inches, and wherein said gelatinous materials are stable in a temperature range between -20° F. and 120° F. to maintain said high suspension yield value.

8. The invention, as defined in claim 1, wherein: a third liquid material of discontinuous phase relative to said first and second bodies is emulsified in one of said bodies.

9. The invention, as defined in claim 1, wherein: a third liquid material of discontinuous phase relative to said first and second bodies is emulsified in one of said bodies to provide an optical contrast in said fluid suspension.

10. An aesthetic fluid suspension comprising:

    - A. A first body of gelatinous material having a high suspension yield value,
    - B. A second body of gelatinous material disposed on the first body of material and suspended therein by the high suspension yield value of the gelatinous material, said second body having a substantially similar suspension yield value as the first body, but having an optical contrast with the first body, and
    - C. A container for suitably enclosing the suspension and through which it may be visible.

11. In an aesthetic fluid suspension, the combination of: a container having an optical window-like structure adapted to optically expose the contents of the interior of said container; a plurality of bodies of gelatinous material having high suspension yield value, said bodies all having optically contrasting characteristics relative to each other so that each of said bodies is distinguishable optically; each of said bodies comprising a different product.

12. The invention, as defined in claim 11, wherein: said plurality of bodies are disposed in generally lay-

- ered superimposed relation to each other in said container.
13. The invention, as defined in claim 12, wherein: one of said bodies comprises a soap product, another of said bodies contains a hair conditioner, and another of said bodies contains a skin conditioning oil.
14. A method for creating an optically contrasting fluid suspension comprising: preparing a first body of gelatinous material having a high yield value and then preparing a second material having an optically contrasting character relative to that of said first body and inserting said second material into said first body.
15. The invention, as defined in claim 14, wherein: second material is introduced into the first body of gelatinous material through a tubular member inserted in said body and then causing relative movement of said tubular member and said body, while delivering said second material through said tubular member to provide a pattern of said second material in said first body.
16. A method for creating an aesthetic fluid suspension comprising: preparing a first body of gelatinous material having a high suspension register value and then preparing a second gelatinous material having a high suspension yield value and which has an having optically contrasting character relative to that of said first body and inserting said second material into said first body and allowing the high yield value of said materials to suspend said second material substantially in permanent position in said first body of material.
17. A method for creating an aesthetic fluid suspension comprising: preparing a first body of gelatinous material having a high yield value, then foaming by dispersing a gas therein a portion of second gelatinous having a high yield value and then inserting the second foamed material into said first body.
18. The invention, as defined in claim 16, wherein: said gelatinous material having a high suspension yield value consists principally of water and a water soluble carboxy vinyl polymer of extremely high molecular weight and said second material is of a different color than the material of said first body to provide for said contrasting character.
19. The invention, as defined in claim 16, wherein: the second material is introduced into the body of the first gelatinous material through a tubular member inserted in said body and then causing relative movement of said tubular member and said body, while delivering said second material through said tubular member to provide a pattern of said similar material in said first body.
20. A method for creating an aesthetic fluid suspension comprising: preparing a first body of gelatinous material having a high yield value, then freezing a portion of a second gelatinous material which may have a high yield value and which has an optically contrasting character relative to the material of said first body and then inserting the frozen portion of said second material into said first body.
21. A method for creating an aesthetic fluid suspension, comprising: preparing a first body of gelatinous material having a high yield value, then freezing a portion of a second body of gelatinous material having optical identity with that of said first, then placing indicia on said portion of material, such that the indicia contrasts optically relative to the first body and the frozen portion, whereby the frozen portion when it thaws out is not optically distinguishable from the material of said body, and whereby said indicia stands alone optically contrasting with the material of said first body and said initially frozen portion.

UNITED STATES PATENT OFFICE
CERTIFICATE OF CORRECTION

Patent No. 3,777,379 Dated December 11, 1973

Inventor(s) WILLIAM B. LEWELLEN

It is certified that error appears in the above-identified patent and that said Letters Patent are hereby corrected as shown below:

Column 6, line 17, "0.25" should read -- 0.025 -- .
Claim 2, line 1 of element a, cancel "a" . Claim 15, line 2, "intorudced" should read -- introduced. Claim 16, line 3 "register" should read -- yield -- ; line 5, "having" should be cancelled. Claim 17, line 4, insert -- a -- before "second"; line 5, insert -- material -- before "having". Claim 18, line 4, cancel "extremely". Claim 21, line 4, after "having", insert -- a high yield value which has an -- ; line 5, after "first" and before the comma, insert -- body -- .

Signed and sealed this 6th day of August 1974.

[57]

ABSTRACT

A method for producing an aesthetic field suspension comprising preparation of a body of gelatinous material having high yield value, then inserting a similar gelatinous material of similar characteristics therein, said similar gelatinous material being optically contrasting with said body of gelatinous material, then allowing the high yield value of the materials to hold the similar material in said body material in substantially permanent position relative to said body; the disclosure further and specifically defining a method for inserting the similar material in said body in frozen form or by means of a hollow tubular member which may be moved around in the body during the insertion of the similar material therein to form geometric or other aesthetic patterns of the similar material in the body material; the disclosure also defining a novel product related to said method.
